UNITED STATES PATENT OFFICE.

WALTER WOOD, OF BAY CITY, OREGON.

ATTACHMENT FOR SHOES.

1,350,197.

Specification of Letters Patent. Patented Aug. 17, 1920.

Application filed December 22, 1919. Serial No. 346,475

To all whom it may concern:

Be it known that I, WALTER Wood, a citizen of the United States, residing at Bay City, in the county of Tillamook and State 5 of Oregon, have invented new and useful Improvements in Attachments for Shoes, of which the following is a specification.

The object of the invention is to provide a simple and inexpensive attachment for shoes 10 adapted to be used in logging operations, in mines, quarries and the like, as a means of protecting the shoes and to serve the purpose of creepers to prevent slipping, etc.; and with these objects the invention consists in 15 a construction, combination and relation of parts of which a preferred embodiment is illustrated in the accompanying drawings, wherein:

Figure 1 is a side view of the device applied in the operative position to a shoe.

Fig. 2 is a bottom plan view of the same.

Fig. 3 is a detail sectional view showing the toe clip.

Fig. 4 is a rear view to show the means 25 for engaging the heel counter.

The frame or body portion of the attachment is in plan in substantially the form of the shoe sole, having a toe member 10 and a heel member 11 both of looped form and 30 constructed of channel iron with the channel disposed to face inwardly. The flanges of the channel on one of the members are removed to form a reduced tongue 12 to be received between the flanges of the other member, so that said members may be 35 adjustably fitted together and secured by bolts 13 engaging registering openings 14 in the members, to adapt the attachment to fit shoes of different sizes. At the sides of the toe

40 member 10 at intermediate points the upper flanges of the frame bar are turned upward to form side clips or ears 15 and at the front end of the toe section there is provided a toe clip 16 adjustably secured to the bar by means of bolts 17 engaging slots 18, and having 45 an inturned upper lip 19 for engagement over the upper edge of the shoe sole as shown in Figs. 1 and 3.

Hingedly mounted to the center of the 50 rear section of the frame is a heel clamp 20 adapted to extend upward in contact with the rear side of the heel and having spurs 21 for engagement with the heel counter, said heel plate being bifurcated at its upper end 55 to form forwardly extending arms 22 lying at opposite sides of the shoe counter and

terminating in loops 23 with which are engaged the extremities of an instep strap 24 having an adjusting buckle 25. Obviously by engaging the toe clip over the front of 60 the shoe or boot sole as indicated in Fig. 1, and then folding the attachment up against the bottom of the shoe or boot and securing the instep strap, the device will be firmly secured to the foot of the wearer and will 65 effectively protect the shoe against wear notwithstanding the rough usage to which devices of this class are subjected.

What is claimed is:—

1. A shoe attachment of the class described consisting of a substantially straight frame corresponding in plan with a shoe sole and consisting of toe and heel members of channel iron adjustably secured together at 70 their meeting ends, the toe member being provided with a toe clip and the heel member with a heel clamp provided with forwardly and upwardly extending arms, and an instep strap connecting said arms.

2. A shoe attachment of the class described having a frame consisting of toe and heel loops of channel iron formed to engage the edges of the shoe and heel, one of said loops having its extremities reduced to form 75 tongues to fit in the channels of the other member, bolts engaging registering transverse openings in the overlapping extremities of said members, the meeting ends of said members bridging the instep of the 80 shoe, a toe clip carried by the toe member, a heel clamp carried by the heel member, and an instep strap connected with said heel clamp.

3. A shoe attachment for the purpose described having toe and heel members of channel iron, the flanges of the toe member at intermediate points being turned up to form ears for engaging the side edges of the shoe sole, a toe clip adjustably secured to 95 the front end of the sole member and having a rearwardly turned extremity for engaging the upper surface of the shoe sole, a heel clamp hingedly connected with the rear portion of the heel member and having counter 100 engaging spurs and upwardly and forwardly divergent arms terminating in loops, and an instep strap connected with said loops and provided with an adjusting device.

In testimony whereof I affix my signature. 110

WALTER WOOD.
